UNITED STATES PATENT OFFICE.

LEWIS J. HANSON, OF SOMERVILLE, MASSACHUSETTS, ASSIGNOR OF ONE-HALF TO
JOSEPH P. McCANN, OF ARLINGTON, MASSACHUSETTS.

CAR REPLACER.

Application filed November 3, 1923. Serial No. 672,546.

To all whom it may concern:

Be it known that I, LEWIS J. HANSON, a citizen of the United States, residing at Somerville, in the county of Middlesex and State of Massachusetts, have invented certain new and useful Improvements in Car Replacers, of which the following is a specification.

This invention relates to improvements in car replacers and more particularly to a car replacer for replacing the wheels of street railway cars on surface tracks.

One of the objects of the invention is to provide a combined left and right hand one-piece plate adapted to be used either between the rails or outside of either rail, the rail chosen being determined by the nature of the derailment. In cases where a wheel is outside of a rail with the flange of the wheel abutting against a paving block or other obstruction, this plate may be used to free the same.

Another object of the invention is to provide a car replacer plate with a number of downwardly extending lugs adapted to engage the groove formed in the paving or other street surface to allow for the flange of the car wheels, or in case of girder rails, the lugs may be placed against the flange of the rail itself. Said lugs are positioned in such manner as to permit the plate to be used in various positions relatively to the rail. If the derailed wheel lies close to the rail, three lugs at one side of the plate may be placed in said groove or against said flange while if the derailed wheel is some distance from the rail, then one of the end lugs only is placed in the groove or against the flange to permit the replacer plate to be swung into the proper position to receive the car wheel.

A further object of the invention is to provide a car replacer having a number of grooves in its upper surface, which may be used to replace car wheels lying at varying distances from the rail.

Another object of the invention is to furnish a car replacer plate of relatively light structure to reduce weight, but sufficiently strong to bear the weight of a street railway car.

With the foregoing objects outlined and with other objects in view which will appear as the description proceeds, the inven-

tion consists in the novel features herein-after described in detail, illustrated in the accompanying drawing and more particularly pointed out in the appended claims.

Referring to the drawing:

Figure 1 is a top plan view of the replacer.

Fig. 2 is a side view of the same.

Fig. 3 is a front end view.

Fig. 4 is a rear end view.

In the drawing the replacer plate consists of a single piece of metal formed by casting or the like, and in practice this plate is about twelve inches long, nine inches wide and about two and one-half inches high at its peak.

The main portion of the plate is inclined upwardly and rearwardly from the front end 1 to the peak 2 and the upper surface of the body adjacent the front end 1 is flattened as shown at 3 to facilitate the passage of a car wheel along the same.

A V-shaped ridge 4 having its point at the front end of the plate, extends along the upper face of the body and the rear extremities 5 of said ridge terminate at the rear edge 6 of the plate. This ridge permits the replacer to be used at either the right or left hand side of the track rail, and if the replacer is placed for instance at the left hand side of the track rails, the portion of the ridge designated 4^a will engage the flange of the wheel while the wheel is traveling up the inclined surface of the plate, and gradually force the wheel outwardly toward the right as the wheel moves up the incline toward the rear edge of the replacer plate. On the other hand if the replacer is placed at the right hand side of the track, the portion 4^b of the ridge functions to force the car wheel toward the track.

Ridges 7 extend upwardly from the opposite side edges of the plate, and shorter vertical ridges 8 extend upwardly from the plate and are spaced from the ridges 7 to provide parallel grooves 9. If the wheel to be replaced lies close to the track rail, then the groove 9 may be employed to guide the wheel as the latter moves up the incline and toward the rear edge 6 of the plate.

Still shorter ridges 8^a are arranged between the ridge 4 and these ridges 8^a are inclined relatively to the ridges 8 to provide substantially V-shaped grooves 9^a, which

may be employed to guide the wheel in case the wheel lies too far from the track to be received by one of the grooves 9.

5 A triangular portion of the plate is removed as shown at 5^a in order to reduce weight, and a cross-bar 6 extends across the rear end of the plate to connect the two legs formed by removing the portion 5^a.

10 The reference character 10 designates the plane of the upper surface of the plate from the flat surface 3 to the peak 2, while the reference character 11 designates the plane forming the upper edges of the ridges 7, 8 and 8^a.

15 Downwardly extending flanges or side bars 4^c form the side edges of the plate and the space between these side bars and beneath the inclined body of the plate, is hollowed out to reduce weight.

20 The rear end of the inclined surface of the body of the plate merges into convex surfaces 6^a, which extend from the peak 2 of the inclined surface to the rear edge 6 of the plate. These convex surfaces 6^a, in practice extend upwardly about two inches, so a car wheel passing over the peak 2 and down the convexed surface 6^a will glide without jarring or breaking the flange of the car wheel.

25 30 The side bars 4^c are provided with depending spaced lugs 12, one of these lugs being arranged near each end of the side bar, and the other lug being arranged intermediate the ends of the side bar. These lugs are so arranged that if the rail wheel lies close to the track, all three lugs at one edge of the plate may be inserted in the track groove or in the groove in the pavement adjacent the track, and these lugs 35 will then prevent shifting of the plate while the car wheel is riding over said plate. If the derailed wheel lies at some distance from the track rail, then one of the end lugs arranged near the rear end 6 of the plate, 40 may be inserted in the track groove or in the pavement groove adjacent the track, and the plate may be swung about this lug to bring the plate into a position to receive the derailed wheel.

45 50 Grooves 1^a are arranged between the ridges 8^a and the ridge 4 and these grooves lead from the entrance or running-on end of the plate to the right and left corners respectively or running-off ends of the plate, 55 and these running-off ends are convexed or rounded, as before stated, to facilitate gliding the wheel on to the rail.

60 The ridges 8^a and 8 in addition to functioning as guides, also strengthen the body of the plate. The hollowed out portion of

the plate beneath the body and between the side bars 4^c, facilitate the arrangement of the replacer over obstructions formed by paving blocks and the like.

65 From the foregoing it is believed that the construction, operation and advantages of the invention may be readily understood without further description, and it is apparent that changes may be made in the details illustrated without departing from 70 the spirit of the invention as expressed in the claims.

What I claim and desire to secure by Letters-Patent is:

1. A car replacer comprising a plate having its upper surface inclined upwardly and rearwardly to a point adjacent the rear edge of said plate, and inclined downwardly from this point to the rear edge, a V-shaped ridge extending upwardly from said plate and having its point adjacent to the front edge of the plate and its ends terminating at the rear edge of the plate, and a plurality of grooves arranged in the upper surfaces of said plate between said ridge and the side edges of the plate. 75 80 85

2. A car replacer as claimed in claim 1 in which said grooves are formed partially by upwardly extending ridges integral with the plate. 90

3. A car replacer as claimed in claim 1 in which said grooves are formed partially by upwardly extending ridges integral with the plate, certain of the last mentioned ridges being substantially parallel to the side edges of the plate, and others of said last mentioned ridges being arranged at angles to the parallel ridges. 95

4. A car replacer as claimed in claim 1 in which a space is provided between the legs of the V-shaped ridge to reduce weight. 100

5. A car replacer as claimed in claim 1 including pendent lugs arranged at the side edges of the plate and spaced apart. 105

6. A car replacer comprising a plate having its upper surface inclined upwardly and rearwardly from one end of the plate to a position adjacent the other end of the plate, parallel ridges extending upwardly from the opposite side portions of the plate, a V-shaped ridge extending upwardly from the upper surface of the plate, having its point merging into one end of the plate and having its lugs diverging toward the opposite end of the plate, and intermediate ridges arranged between the V-shaped ridge and said side ridges. 110 115

In testimony whereof I affix my signature.

LEWIS J. HANSON.
